(57) **CLAIM**

The ornamental design for razor-trimmer, as shown and described.

DESCRIPTION

Figure 1.1 is a top perspective view of a razor-trimmer showing my new design;

Figure 1.2 is a rear elevational view thereof;

Figure 1.3 is a left side view thereof, the right side view being a mirror image thereof;

Figure 1.4 is a bottom plain view thereof;

Figure 1.5 is a front elevational view thereof;

Figure 1.6 is another perspective view thereof; and

Figure 1.7 is a top plain view thereof; and

Figure 1.8 is a right side view thereof.
